UNITED STATES PATENT OFFICE

MAXWELL M. UPSON, OF ENGLEWOOD, NEW JERSEY, ASSIGNOR TO RAYMOND CONCRETE PILE COMPANY, OF NEW YORK, N. Y., A CORPORATION OF NEW JERSEY

COMPOSITE PILE

Application filed May 19, 1928. Serial No. 278,942.

This invention pertains to composite piles and is an improvement on the invention disclosed in my copending application Serial No. 143,565, filed October 23, 1926, for "sinking composite piles". That application discloses a method and apparatus for sinking composite piles, especially composite piles comprising a lower section of wood and an upper section of concrete. In the copending application the method disclosed for joining the wood and concrete sections is generally satisfactory, but under certain circumstances, when the pile is subject to unusual lateral stresses, it is found desirable to provide a joint better able to resist such stresses.

The principal object, therefore, of the present invention is to disclose an improved form of joint between sections of composite piles.

Further and other objects and advantages will be hereinafter set forth in the accompanying specification and claims, and shown in the drawings, which by way of illustration show what is now considered to be the preferred embodiment of the invention.

Fig. 1 is a view, partly in cross-section, of the upper end of the lower section of a composite pile, with removable shell in place and driving mechanism in position.

Fig. 2 is a cross-section of the upper end of lower section and lower end of upper section prior to removal of the removable shell.

The lower pile section, designated 10, is provided at its upper end with a tenon 12, and, below the tenon, a turned portion 14, which leaves a shoulder 16 where it joins the body of pile 10.

Tenon 12 is bored at its top and provided with a screw socket 18, held in place by a cross pin 20. A reinforcing bar 22 is screwed 40 into socket 18.

By means of hammer 24, through follower 26 fitted to tenon 12 as shown in Fig. 1, pile section 10 is driven until shoulder 16 is near ground level. According to the above co-pending application, the shell 30 is then slipped over turned portion 14 and the driving is resumed, shell 30 being driven with pile 10 until the desired depth is reached. Then rod 22 is screwed into place, shell 30 is filled with concrete which surrounds the

tenon and reinforcing rod, shell 30 is removed, and the operation is complete.

In the present invention, however, a somewhat different procedure is followed after the lower section has been driven to ground level. Before applying removable shell 30 to turned portion 14, another shell or sleeve 32 is first put in place. Sleeve 32 is of comparatively thin material, preferably steel. It is slipped over turned portion 14 and its lower end is crimped as at 34, into a groove 36 turned in 14 just above shoulder 16. Shell 30 is then slipped over sleeve 32 to rest on shoulder 16, and the pile and shell 30 are driven as before, to the desired depth.

At that point in the operation an upper pile section 40 of precast concrete, reinforced if desired, is lowered into place on tenon 12, within shell 30 and sleeve 32. This precast section 40 is provided with a central bore 42 and a radial passage 44 from bore 42 to the outside of the section.

After section 40 is in place the upper end of sleeve 32 is crimped against section 40 as at 46, rod 22 is screwed into socket 18 and grout is poured from above into bore 42 from which it flows through channel 44 into the annular space 48 between pile section 40 and crimped sleeve 32. Shell 30 is afterwards removed.

It will be appreciated that the above arrangement securely locks the concrete member 40 to the sleeve 32, thereby providing a tension and compression reinforcement extending around the entire joint and locking the two pile sections together. Sleeve 32 greatly increases the section modulus through the joint and the strength of the joint is increased accordingly.

It is to be understood that the invention is not limited to the construction herein specifically illustrated but can be embodied in other forms without departure from its spirit as defined by the following claims.

I claim:

1. In a composite pile, in combination, a lower section having a tenon on its upper end, a hollow upper section having a lower end adapted to surround said tenon, a sleeve closely surrounding said lower section below said tenon and extending upwardly around

said upper section but spaced therefrom to form an annular space between said upper section and said shell, means for sealing the space between the upper end of said sleeve and said upper pile section, and a passage 5 connecting said annular space with the hollow interior of said upper section whereby when said hollow interior is filled with freshly mixed concrete the concrete will flow through said passage into said annular space to form therein a concrete shell to reinforce the joint between said pile sections.

10 2. In a composite pile, in combination, a lower section, an upper section, a turned portion at the upper end of said lower section, a circumferential groove in said turned portion, a metallic sleeve surrounding said turned portion and extending above said lower pile to form an annular space between said sleeve and the lower portion of said upper pile section, the lower end of said sleeve being crimped into said circumferential groove and the upper end of said sleeve being crimped against said upper pile section, and a concrete shell formed by pouring grout into the annular space between the sleeve and upper pile section.

15 3. The invention set forth in claim 2 in which a passage is provided from said annular space to a cavity in said upper pile section, and said annular space is filled by grout forced through said cavity and passage.

20 4. In the method of forming a composite pile having an upper section resting on a lower section, the steps of placing a shell to surround the upper end of the lower section and the lower end of the upper section whereby an annular space is provided between said upper section and said shell, attaching said shell to said lower section, sealing the upper end of said shell against the upper pile section to prevent leakage of grout therethrough, and filling said annular space with grout for the purpose set forth.

25 5. In the method of forming a composite pile having a lower section with a tenon and an upper section having a lower end surrounding said tenon, the steps of placing a metallic sleeve to surround the upper end of the lower section and the lower end of the upper section, whereby an annular space is provided between said upper section and said shell sealing the upper and lower ends of said shell against said pile sections to prevent leakage of grout, and filling said annular space with grout to form therein a shell of concrete whereby said tenon, said metallic sleeve, and said concrete shell cooperate to strengthen the joint between said sections.

60 In testimony whereof I hereto affix my signature.

MAXWELL M. UPSON.
